UNITED STATES PATENT OFFICE

121,385

DESIGN FOR A BADGE OR SIMILAR ARTICLE

Stiles M. Decker and Norman H. Beard, Houston,
Tex.

Application February 20, 1940, Serial No. 90,382

Term of patent 3½ years

To all whom it may concern:

Be it known that we, Stiles M. Decker and Norman H. Beard, citizens of the United States, residing at Houston, in the county of Harris and State of Texas, have invented a new, original, and ornamental Design for a Badge, or Similar Article, of which the following is a specification, reference being had to the accompanying drawing, forming a part thereof,

We claim:

The ornamental design for a badge or similar article, as shown.

STILES M. DECKER.
NORMAN H. BEARD.
